SYRINGE

Luis H. Tejera, Central Islip, N.Y., assignor to
Mallinckrodt Chemical Works, St. Louis, Mo.

Filed June 10, 1970, Ser. No. 23,423

Term of patent 14 years

Int. Cl. D24—03

U.S. Cl. D83—12

Fig. 1.

Fig. 2.

Fig. 3.

Fig. 4.

Fig. 6.

Fig. 5

Fig. 7.

Fig. 8.

FIG. 1 is a front elevation of a syringe showing my new design;

FIG. 2 is a side elevation thereof;

FIG. 3 is a rear elevation thereof;

FIG. 4 is a top plan view thereof;

FIG. 5 is a bottom plan view thereof;

FIG. 6 is an elevation similar to FIG. 1, with syringe piston in raised position; and

FIGS. 7 and 8 are perspective views thereof.

I claim:

The ornamental design for a syringe, as shown.
